ROAD SIGN STANDARDS

Lowell C. Carpenter, 8084 SE. 15th Ave., Portland, Oreg.
Filed May 26, 1958, Ser. No. 737,696
5 Claims. (Cl. 40—125)

My invention relates to a collapsible road sign standard for display of various kinds of road warning signs. It is of such a design that the sign is freely swingable which eliminates the tendency of the standard to be blown over or upset by wind gusts created by natural forces and the passage of vehicles.

One of the objects of my invention is to provide a road sign standard that will pivotally mount the warning sign.

A further object of my invention is to provide a portable and collapsible road sign standard that will not easily be upset by wind gusts.

A still further object of my invention is to provide a collapsible and portable road sign standard that is simple, inexpensive and effective.

Other and further objects of my invention will be apparent from the drawings, specifications and claims herein.

Referring to the drawings:

FIG. 1 is a front elevational view of the collapsible and portable road sign standard with a sign mounted thereupon.

FIG. 2 is an end elevational view of the collapsible and portable road sign standard, showing a portion of an arc traced by the lower end of the sign as it swings.

FIG. 3 is a fragmentary detail end view on an enlarged scale, showing the mounting of a sign to the pivoted crossbar, the pivotally mounted leg and stop element therefor and the fixed leg.

Referring further to the drawings:

The collapsible sign standard consists of two end plates 10. Each end plate 10, which is preferably formed from flat stock, has rigidly attached to one side edge thereof a leg 11 which is preferably formed from angle iron. To the opposite side edge of the plate 10 a leg 12 is pivotally attached by means of a bolt, pin or rivet 13. Each plate 10 is also provided with a centrally positioned hole near its top marginal edge and also has a substantially L-shaped stop element 14 rigidly secured to its lower marginal edge in such a position that the leg 12 will be prevented from further outward travel once it has reached the fully opened position. If desired, the end plate 10 and stop 14 may be formed as a one-piece unit, for casting these elements as one unit from a ductile steel has been found to be very satisfactory. The leg 12 is likewise preferably formed from angle iron; and a pin, or other stop element, 15 is inserted into matching holes drilled through said leg 12 and the stop element 14. The holes in each of these elements align when the leg 12 is in the fully opened position. Pin 15 inserted through said holes prevents the leg 12 from pivoting toward or closing with leg 11. A lateral brace element 16 ties the two legs 12 together at a point which is a short distance above the bottom ends or feet 18 of said legs 12. The rigidly secured legs 11 are also tied together by a lateral brace element 17 secured a short distance above the feet 19 of said legs. Gusset bars 16' are rigidly secured to the lateral brace 16 at each end thereof on an angle of approximately 45° to said brace 16 and the adjacent collapsible leg 12. Gusset bars 16' are likewise secured in this same relative position at each end of the lateral brace 17 between it and the legs 11.

A sign-carrying bar 20, preferably fabricated from angle iron, is pivotally secured between the end plates 10 near the top marginal edges thereof by means of element 21 which is preferably a rivet, bolt, pin, etc., inserted

2

through said hole near the top marginal edge of each of said plates 10 in such a manner that it cannot be pulled on through the hole, such as having an enlarged head which forms a shoulder against the outer surface of the plate 10. The rivet 21, however, will freely move rotatably within said hole. The inner end of each of said rivets, etc., 21, is rigidly secured to a portion of the face surface near the end of the sign-carrying bar 20 by welding or other suitable means. A washer 22 is provided between each end of the sign-carrying bar 20 and its adjacent end plate 10, said washers being placed upon the rivets 21 before the same are secured to the sign bar 20. It is preferred to secure the rivets 21 to the flat face surfaces of the sign bar 20, substantially as shown in the drawings. However, the inner ends of the rivets 21 may be secured at the inside corner formed on the back surface of the angle iron sign-carrying bar 20. The latter attachment arrangement makes the actual assembly and alignment of the sign bar easier.

20 A flag holder 24 of any suitable stock such as tubular, etc., is secured medially of the sign-carrying bar 20 on the back side thereof and preferably disposed at an angle of approximately 45° thereto. A flag 27 may be inserted in the flag holder 24, if desired. Storage or carrying straps 25 23, generally hook-shaped in design, are secured near each end of the sign bar 20 in such a manner that the whole sign standard may be stored thereby, hooked over the tailgate of a truck, etc. A sign 25 is detachably secured to the sign bar 20 in any suitable manner such as by 30 bolts 26. Said sign 25 is so positioned that it will clear each of the end plates 10 and will also miss the lateral brace elements 16 and 17 when it is caused to swing to and fro by any means such as the action of natural wind gusts or by any gusts or air currents caused by the passage 35 of vehicles. The sign 25 should be mounted in such a position upon the sign bar 20 that a substantially greater portion of its vertical weight will depend below the sign bar. This manner of attachment causes the sign to present an unbalanced surface to any wind gusts or air currents, 40 so that the sign will readily yield to such currents rather than create a pressure against the standard itself, thus tending to cause upset or blowdown. If the sign 25 were to be mounted too closely to the exact vertical midpoint thereof, a substantially balanced arrangement would 45 be effected which would tend to create the undesirable results of the sign assuming an attitude difficult for motorists to see in calm weather and also of presenting a balanced surface to wind gusts, so that the leverages against the top portion and lower portion of the sign 50 would tend to offset each other and thereby present an unyielding surface to the wind.

The foot ends 18 and 19 of the legs 12 and 11, respectively, are preferably so formed that their bearing surfaces will be disposed at substantially a 90° angle to the longitudinal front and rear edges of each leg. This arrangement presents sharp pointed bearing surfaces to the road shoulder or roadway upon which the standard may be placed, and the feet 18 and 19 of said legs thus tend to dig in and further resist the tendency of the standard to 55 be upset or collapsed by wind gusts or currents.

It is understood that certain variations or modifications of the disclosures herein specifically set forth are feasible without departing from the spirit of my invention and that I am not, therefore, limiting myself to the specific 60 disclosures herein set forth which are merely preferred embodiments of my invention.

Having thus described my invention, what I claim is:

1. As an article of manufacture, a collapsible and portable road sign standard consisting of the combination of: 70 two end plates, each provided with a hole therethrough near the top marginal edge, a leg fixedly secured at one marginal side of said plate and in angular relation thereto,

another leg pivotally secured to said end plate in an angular relation thereto at the marginal side thereof opposite the fixed leg, said pivotal leg being provided with a hole therethrough below the point of its pivotal attachment, and a stop element fixedly secured to the lower marginal edge of said end plate at the edge thereof to which the pivotally mounted leg is attached, said stop element being extended outwardly beyond said pivotally mounted leg, being bent through an angle at its outer end to overlap the front surface of said leg and being provided with a hole therethrough adapted to align with said hole in said pivotal leg; means insertable in said aligning holes in each of said legs and said stop elements; a lateral brace in combination with angular gussets securing each pivotally mounted leg to the other, said brace being positioned near the lower ends of said pivotally mounted legs; a lateral brace in combination with angular gussets securing each rigidly attached leg to the other, said lateral brace being secured near the lower ends of said brace; a sign-carrying bar positioned between said end plates and the holes therethrough; pivotal means inserted through the holes in said end plates and secured to said sign-carrying bar; means medially of said end plates adapted to attach a road warning sign to said sign-carrying bar; two straps rigidly secured to said sign-carrying bar, one near each end thereof, said straps being adapted for storage or, selectively, carrying purposes; tubular means disposed upon and at an angular relation to said sign-carrying bar medially thereof, a flag disposed in said tubular means; and a foot at the lowermost end of each leg, said foot disposed at substantially a 90° angle to the front and rear longitudinal edges of the leg.

2. As an article of manufacture, a collapsible and portable road sign standard consisting of the combination of: two end plates, each provided with a hole therethrough near the top marginal edge and with an integrally formed stop element extending beyond one of the side edges thereof, said stop element having its outer end bent at an angle toward the stop element on the other end plate and having a hole therethrough near its bent end, a leg fixedly secured at the opposite marginal side of said end plate and in angular relationship thereto, another leg pivotally secured to said end plate at an angular relation thereto at the same marginal side thereof on which the said stop element is formed, said leg being provided with a hole therethrough below its point of pivotal attachment aligning with said hole in said pivotal leg when said leg is fully opened and adjacent to the bent outer end of said stop element; means insertable in said aligning holes in said leg and said stop element; a lateral brace in combination with angular gussets securing each pivotally mounted leg to the other, said brace being positioned near the lower ends of said pivotally mounted legs; a lateral brace in combination with angular gussets securing each rigidly attached leg to the other, said lateral brace being secured near the lower ends of said brace; a sign-carrying bar positioned between said end plates and the holes therethrough; pivotal mounting means inserted through the holes in said end plates and secured to said sign-carrying bar; a road warning sign to said sign-carrying bar; two straps rigidly secured to said sign-carrying bar, one near each end thereof, said straps being adapted for storage or, selectively, carrying purposes; tubular means disposed upon and at an angular relation to said sign-carrying bar medially thereof; a flag disposed in said tubular means; and a foot at the lowermost end of each leg, said foot disposed to present a sharp edge to a road surface.

3. In a collapsible and portable road sign standard the combination of: two end plates, each provided with a hole therethrough near the top marginal edge; a leg pivotally secured at one marginal edge of each of said plates, said leg being provided with a hole therethrough below the point of its pivotal attachment; a stop element secured to the lower marginal edge of each end plate, bent inwardly at a right angle to itself at a point outwardly from

said pivotally attached leg and being provided with a hole therethrough adapted to align with said hole in said pivotal leg; means secured to said stop element and insertable in said aligning holes in each leg and stop element adapted to retain said pivotal leg in the fully extended position; a rigidly attached leg secured at the edge of each end plate opposite the pivotally mounted leg; brace elements securing each pivotally mounted leg to the other; brace elements securing each rigidly attached leg to the other; a sign-carrying bar positioned between said end plates; pivotal mounting means inserted through the holes in said end plates, secured to pivotally carry said sign bar between said end plates; a road warning sign detachably secured medially of said pivotally mounted sign bar; means rigidly secured medially of said sign-carrying bar adapted for storage or, selectively, carrying said road sign standard; tubular means disposed upon and medially of said sign-carrying bar, said means adapted to carry a warning flag; and a sharp foot at the lowermost end of each leg of said standard.

4. In a collapsible and portable road sign standard the combination of: two end plates, each provided with a hole therethrough near the top marginal edge and with an integrally formed stop element, bent inwardly at its outermost end and extended beyond one of the side edges thereof; a leg fixedly secured at the marginal edge of each of said plates; another leg pivotally secured to the opposite marginal edge of each of said plates, inwardly from and adjacent to the bent outer end of said stop element, said leg being provided with a hole therethrough below its point of pivotal attachment, said stop element being provided with a hole therethrough adapted to align with said hole in said pivotal leg; means secured to said stop element and insertable in said aligning holes in said leg and said stop element adapted to retain said pivotal leg in the fully extended position; brace elements securing each pivotally mounted leg to the other; brace elements securing each rigidly mounted leg to the other; a sign-carrying bar positioned between said end plates; pivotal mounting means inserted through the holes in said end plate and secured to said sign bar between said end plates; fastening means medially of said end plates and on said sign-carrying bar; a road warning sign detachably secured to said sign bar by said fastening means; means rigidly secured medially of said sign-carrying bar adapted for storage or, selectively, carrying said road sign standard; tubular carrying means disposed upon and medially of said sign-carrying bar; a warning flag mounted in said tubular carrying means; and a foot at the lowermost end of each leg of said standard, said foot adapted to present a sharp surface to a roadway.

5. As an article of manufacture: a collapsible road sign adapted to fold for moving from place to place; a pair of supporting legs; a connecting plate by which each pair of legs is held in a predetermined position of one leg to the other, one leg of each pair being rigidly attached to its connecting plate and the other leg of each pair being swivelly mounted upon said connecting plate; a stop element rigidly secured to said connecting plate and adapted to limit the outward movement of the swivelly connected leg from its respective leg rigidly attached to the connecting plate; a brace element between the swivelly mounted supporting legs; another brace element between the supporting legs rigidly mounted; a sharp pointed foot element at the bottom of each supporting leg, adapted to prevent creeping of any of said legs upon the surface supporting the collapsible sign; a panel adapted for sign display purposes; a swivelly mounted panel supporting means between the supporting legs connecting plates, said sign display panel being so mounted upon the swivelly mounted supporting means that a substantially larger portion of both its weight and area shall be below its attachment to its swivelly mounted supporting means; a flag holder attachment mounted upon the pivotal supporting means; and a pair of hook-shaped carrying straps

extending upwardly from the swivelly mounted supporting element to which the sign-bearing panel is attached.
